MULTIPLE FUSE

Herman Altschule, Newark, N. J., assignor to
 Utility Electric Corp., East Newark, N. J., a corporation of New Jersey

Application February 24, 1941, Serial No. 380,121

5 Claims. (Cl. 200—125)

This invention relates to new and useful improvements in multiple fuses, and particularly in plug fuses of the indicator type.

It is the object of the present invention to provide a multiple indicator fuse which can be readily assembled of simple and inexpensive parts, and which will withstand the fusing of the links.

With this object in view, I shall now describe a preferred embodiment of the invention and certain modifications thereof.

In the drawing, Fig. 1 is a vertical cross-section of a multiple fuse assembled in accordance with the present invention;

Fig. 1—*a* is a horizontal cross-section along lines 1—*a*—1*a* of Fig. 1;

Figs. 2, 3, and 4 are vertical cross-sections of three modifications of the arrangement of the explosion chamber;

Fig. 5 is a vertical cross-section of a modified mounting for the resistor; and

Fig. 6 a cross-section of a modified mounting for the gaseous discharge tube.

Referring now to the drawing, 1 is a base substantially cup-shaped with its upstanding straight side walls 2 enclosing the combustion chamber. The base 1 is made of porcelain and has a central perforation 3 through its bottom. The bottom of the chamber adjacent the side wall 2 is provided with a circumferential annular groove 4. The outside of the side wall 2 is provided with a helical ridge 5 which constitutes a screw thread with which a screw-threaded shell 6 cooperates. The inside surface of the side wall 2 is provided with a plurality, e. g., six vertical grooves extending from the annular groove 4 all the way to the lip or rim of wall 2. These grooves are equidistant and within each groove is placed a fusible link 7 made of zinc or the like. One end of each link 7 projects down to the bottom of the annular groove 4 and the other end is bent around the rim of the wall as indicated at 8. These links are each approximately $\frac{1}{8}$ of an inch wide and contain a weakened portion about $\frac{1}{8}$ of an inch wide located in the vertical portion of the link. The links 7 are held firmly in position by a flange 9 formed in the shell 6.

In assembling the fuse, first the links 7 are put in place in the base and clamped by means of the shell 6. Then a copper rivet 10 is inserted through the central perforation 3 until head 11 of the rivet engages the bottom of the base 1.

The next step is to slip a contact wiper 12 over the rivet 10 until it comes to rest on the bottom of the combustion chamber. The wiper 12 is resiliently engaged by cover 16.

is formed out of a phosphor bronze spring, the end of which, as indicated at 13, is bent around the rivet 10. The wiper 12 engages the links 7 and also the wall between the links and will thus be cleaned when it is rotated from one link to the next.

On top of the wiper 12 is placed a fiber disk 14 having an ear 15 and a central perforation through which the rivet projects.

The next operation is to place on the base, as thus far assembled, a top or cover 16 formed of any suitable insulating material. The cover 16 has three concentric annular sleeves projecting from the bottom face thereof, 17, 18, and 19. The first sleeve projects near the rim of the top 16 on the outside of shell 6 slightly below the rim of wall 2. The second sleeve 18 has such an outside diameter that it fits within the explosion chamber adjacent links 7. The end of sleeve 18 projects within the annular groove 4 in the bottom of the chamber. A longitudinal slot 20 is formed in the sleeve 18 from the open lower end up to a point slightly below the rim of the wall, and having a width of about $\frac{1}{8}$ of an inch corresponding to the width of a link 7. The wiper 12 projects through this slot 20 into engagement with the side wall of the chamber and so does the finger 15 formed in the fiber washer 14. The third sleeve 19 surrounds the rivet 10 and terminates on top of the fiber washer 14. This sleeve is open through a central perforation in top 16 around which a depression 22 is formed. A metal washer 23 is placed within the depression 22 and the projecting end of the rivet 10 is headed over as indicated at 24 to clamp together the whole assembly.

A resistor 25 is then placed into an opening 26 in top 16 until it comes to rest on the turned-in flange 9 of the shell 6 which is in alignment with the opening 26. The resistor 25 is held down against the flange 9 by a leaf spring 27 which is fastened to the top 16 by means of a drive screw 28.

An electric gaseous discharge or incandescent lamp is now connected in place above cover 16. The lamp has a glass envelope 30 enclosing, in a neon atmosphere, two electrodes 31 from which lead-in wires 32 and 33 pass through the envelope to the outside. Lead-in wire 32 is soldered to screw 28 and lead-in wire 33 to the head of rivet 10.

A cover 34 having an opening 35 is placed over lamp 30 and fastened to top 16 by any suitable means, such as a ridge (not shown) projecting from 16 and resiliently engaged by cover 34.

The plug is now fully assembled and in condition to be screwed into the customary fuse socket having a shell cooperating with the screw shell 6 and a central terminal engaged by head 11 of rivet 10. When the fuse is thus in position an electrical circuit is closed from the central terminal to the fuse socket through rivet 10, wiper 12, fuse link 1 on which the wiper is resting, shell 6, to the shell of the socket. If there is a sudden surge of excessive current or short circuit in the supply circuit, the link will fuse breaking this circuit and permitting the flow of sufficient current in the lamp circuit so that the lamp will light. This lamp circuit may be traced over rivet 10, lead-in wire 33, electrodes 31, lead-in wire 32, wiper 21, resistor 25 and shell 6.

When the lighting of the lamp 31 is noticed, the top 16 is rotated and the wiper 12 and fiber disk 14 are forced to rotate therewith on account of their engagement by the lateral walls of the notch 20 in the second sleeve 18 formed in the top. The rivet 10 will also turn with the top as will the resistor 25 which is held in firm engagement with the flange 9 by the spring 27. The fuse will be ready for a second operation when the wiper 12 is stopped on the next link 7.

The products of combustion from the fusing of a link 1 will travel from the annular chamber formed between sleeves 18 and 19 through the slot 20, and then out between the contacting surfaces of top 16 and shell 6 which do not fit very tightly, top 16 being slightly hollowed out between sleeves 17 and 12 in alignment with slot 20, as indicated at 29.

In the modification illustrated in Fig. 2, top 16a has only two instead of three depending sleeves; 17a and 19a. The sleeve 19a is longer than the sleeve 19 of Fig. 1 and extends to the bottom of the chamber. It has, however, a notch 40 cut therein through which wiper 12 projects into engagement with the side walls of the cavity. In lieu of the second sleeve 18 and a separate fiber disk 14, a cup is formed having a side wall 18a and a bottom 14a. The diameter of the cup is the same as the diameter of the sleeve 18, and the bottom 14a corresponds to the fiber disk 14 and rests on top of the wiper 12. The upper ends of the side wall 18a project within a sector shaped groove 41 provided in the lower face of top 16a. The side wall 18a has a longitudinal notch 20a cut therein corresponding to notch 20 in the sleeve 18 so as to afford as large an explosion chamber as is feasible. In all other respects the construction and assembly will be identical with Fig. 1.

In the modification shown in Fig. 3, top 16b is again provided only with two downwardly projecting sleeves; 17b and 19b. The fiber washer 14 of Fig. 1 is retained and the inside sleeve 19b has the same length as sleeve 19 has in Fig. 1. In fact, the only difference between Figs. 1 and 3 is that instead of being integral with the top 16, the second sleeve is formed as a separate piece 18b having a vertical notch 20b through which the finger 15 on washer 14 and the wiper 12 project. The lower end of 18b is seated in the groove 4 and the upper end within a groove 41b formed in the lower face of the top 16b.

The constructions shown in Figs. 2 and 3 permit the use in the walls of the sleeves 18a and 18b materials having greater resistance to heat than is required for the top 16.

Fig. 4 shows still another embodiment in which the first and the second sleeves 17c and 18c are integral with top 16c. The third sleeve is

made of a separate piece 19c which has special heat resistant qualities to protect the rivet. The fiber washer 14 and all the other parts will be the same as in Fig. 1.

5 The resistor 25, as shown in Fig. 5, may be held within an opening 42 provided in the lower face of top 16d and having a small hole 43. Within the cavity a coiled spring 27d is provided, the end of which projects through the opening 43 for connection with the lead-in wire 32.

In the embodiment shown in Fig. 6, instead of providing a separate lamp cover 34, the top 16e is provided with a rim 45 within which is seated a window 46 of Plastocel or other suitable transparent material. The discharge lamp is provided within the cavity thus formed and may be viewed through the window 46.

Other modifications will be obvious to those skilled in the art without departing from the spirit of the invention defined in the claims.

What is claimed is:

1. In a multiple fuse, a base having a bottom and side walls enclosing an explosion chamber; a plurality of fusible links within said chamber against the side wall; a metal shell around said base and connected with said links; a rotatable top for said base; two concentric sleeves within said chamber the first projecting from the bottom to the top of the chamber and the second from a point above the bottom to the top; a rivet projecting through the base and one of said sleeves; a wiper mounted on said rivet projecting through a slot in one of said sleeves into contact with the links; a resistor directly contacting with said shell and rotatable with the top; and an electric lamp above said top connected between the rivet and said resistor.

2. In a multiple fuse, a base having a bottom, and side walls enclosing an explosion chamber; 40 a plurality of equally spaced fusible links within said chamber against the side wall; a screw-threaded metal shell around said base and connected with said links; a rotatable top for said base; two concentric sleeves within said chamber 45 the first projecting from the bottom to the top of the chamber and the second from a point above the bottom to the top; a rivet projecting through the base, one of said sleeves and said top; a wiper mounted on said rivet and projecting through a slot in one of said sleeves into contact with the links; a resistor projecting into direct engagement with said shell through a perforation of said top and rotatable therewith; and an electric lamp above said top having a 55 lead-in wire connected to the rivet and a second lead-in wire to said resistor.

3. In a multiple fuse, a base having a bottom and a side wall enclosing an explosion chamber; a plurality of equally spaced fusible links against 60 the inside surface of the side wall with their ends bent over the rim thereof; a screw-threaded metal shell around the base and clamping the bent-over ends of the fusible links; a rotatable top for said base having two concentric sleeves 65 projecting into the chamber, the first adjacent the wall to the bottom and having a longitudinal slot of substantially the same width as one of said links, and the second centrally to a point above the bottom; a rivet projecting through and holding together the base, said second sleeve and said top; a contactor having one end fastened to said rivet and the other end formed into a wiper 70 projecting through the slot in the first sleeve into contact with the side wall and the links; a washer 75 on said rivet between said contactor and the lower

end of the second sleeve and closing the chamber formed between the first and second sleeves with an ear projecting within the slot, said contactor and washer being rotatable with said top; a resistor projecting through a perforation of said top and rotatable therewith; a spring pressing said resistor into direct engagement with the shell; an electric lamp above said top and having a lead-in wire connected to said rivet and a second lead-in wire connected to said resistor; and a cover for said lamp on said top.

4. In a multiple fuse plug, a cup-shaped porcelain base the bottom of which is perforated and has a circumferential annular groove in the inside surface from which rise a plurality of equally spaced vertical grooves in the side wall up to the lip, and a helical ridge formed in the outside surface of the side wall; a fusible link within each vertical groove with one end projecting in said annular groove and the other end bent over the lip, and having a weakened portion between said lip and annular groove; a screw-threaded metal shell engaging said helical ridge and having a turned-in flange seated on the lip of the base and clamping the bent-over ends of the fusible links; a rotatable top for said base having a cover and three concentric sleeves projecting therefrom, the first near the edge to a point slightly below the lip of the base on the outside of said shell, the second within said annular groove in the base and having a longitudinal slot of substantially the same width as one of said fusible links, and the third centrally within the second and extending to a point above the bottom of the base; a copper rivet projecting through the perforation in the bottom of the base and said third sleeve and having a head engaging the bottom of said base and a second head above the cover of said top; a metal washer in a recess of said cover engaged by the second head of the rivet, said rivet and washer being

5 rotatable with said top; a metal contactor having one end surrounding said rivet at the bottom of the cup and the other end formed into a wiper projecting through the slot in the second sleeve into contact with the inside wall of the base and the links within the grooves; an insulating washer on said rivet clamped between said contactor and the lower end of the third sleeve and closing the chamber formed between the third and second sleeves with an ear projecting into the slot, said contactor and washer being rotatable with said top; a resistor projecting through a perforation of said cover between the first and second sleeves and rotatable therewith; a leaf spring having one end fastened to said cover and the free end bearing against said resistor to press it into engagement with the shell flange; a gaseous discharge lamp having a lead-in wire connected to the second head of said rivet and a second lead-in wire connected to said spring; and a cover for said lamp fastened to said top and having an opening through which the lighting of said lamp can be observed.

10 15 20 25 30 35 40 5. In a multiple fuse plug, a base having a bottom and side walls enclosing an explosion chamber; a plurality of equally spaced fusible links against the inside surface of said chamber; a screw-threaded metal shell around said base and in contact with said links; a rotatable top for said base; two concentric sleeves within said chamber, one integral with the top and the other separate; a rivet projecting through the base, one of said sleeves and said top; a wiper mounted on said rivet and projecting through a slot in a sleeve and into contact with the links; a resistor mounted on and rotatable with said top, there being a direct connection between said shell and resistor in all positions of the latter; an electric lamp connected between said rivet and resistor; and a cover for said lamp on said top.
